RICHARD K. HOHMANN, OF BELVIDERE, ILLINOIS, ASSIGNOR TO NATIONAL SEWING MACHINE COMPANY, OF BELVIDERE, ILLINOIS, A CORPORATION OF ILLINOIS.

BOBBIN-HOLDER FOR ROTARY-HOOK MACHINES.

1,105,197.

Specification of Letters Patent.

Patented July 28, 1914.

Application filed May 5, 1913. Serial No. 765,419.

To all whom it may concern:

Be it known that I, RICHARD K. HOHMANN, a citizen of the United States, residing at Belvidere, county of Boone, State of Illinois, have invented certain new and useful Improvements in Bobbin-Holders for Rotary-Hook Machines, of which the following is a specification.

This invention relates to the holder or race which carries the bobbin containing the lower thread in revolving hook sewing machines.

One purpose of the invention is to economize space, making it possible to use a larger bobbin carrying a much larger amount of thread than has been possible with races of the same size in any previous construction known to me.

A further object of the invention is to place proper tension on the thread carried by the bobbin by simple mechanism involving nothing more than the retaining means for the bobbin.

The novel features of the invention will be apparent from the following description taken in connection with the drawings.

In the drawings: Figure 1 is a side view of a bobbin holder embodying my invention. Fig. 2 is a cross section on the line 2--2 of Fig. 1.

It is of course well known that in revolving hook sewing machines the bobbin for the lower thread is carried in a race or holder around which the revolving hook moves, the loop of thread being carried by the revolving hook and spread around the bobbin holder so as to form the lock stitch, the upper thread interlocking with the lower thread. In the present case I have shown only the bobbin holder but am filing another application herewith relating to the particular machine in which this holder is used, and since those skilled in the art will understand the necessary features of the invention which coöperate with the bobbin holder it is not necessary to show those features in the present case.

As shown in the drawings my bobbin holder or race includes a casing having a circumferential bearing rim 1 which serves to support the holder when it is in use in the machine, this bearing rim fitting in a bearing groove and the holder being held by means, not shown, for preventing it from rotating as the revolving hook passes around

it. In the form shown the bearing rim 1 is cut away at the top and a hook 2 is formed near the top on one side facing the top so as to catch and spread the thread as it is being carried around the holder. The holder 60 has a rear wall 3 and opposite that wall in the face of the holder there is an opening circular in form of the right size to receive the bobbin 4. This circular opening is not concentric with the bearing rim 1, but, 65 on the contrary, is arranged eccentric thereto, its axis being to one side of and in substantially the same horizontal plane as the axis of the bearing rim. The end walls 5 and 6 are inclined from the bearing rim outwardly to the edge of the circular bobbin holding space, and since the bobbin is eccentrically arranged in the holder the walls 5 and 6 will not be at such a steep inclination 70 as the walls 7 and 8 on the opposite side of the holder nearest the bobbin space. A hollow column or shaft 9 is secured to the rear wall 3 centrally of the bobbin space and it projects toward such opening in the opposite wall and is adapted to receive the bobbin 4, which has the central bearing opening fitting this shaft. As will be seen by reference to Fig. 2 the shaft 9 is somewhat shorter than the bobbin so that the end wall of the bobbin is somewhat beyond the end of the 75 shaft. In order to hold the bobbin in place in the holder and to give it the necessary tension a spring 10 is used within hollow shaft 9 and a member 11 extends down into that shaft and is adapted to be pressed inwardly by the spring. A retaining arm 12 is pivoted at 13 to the end of the member 11 and is adapted to be turned down to the position shown in Fig. 1, extending downwardly at an angle of about 45° on the same 80 side of the holder as that on which the hook 2 is placed. This arm can be turned up until it is in line with the member 11 and then the hook or bobbin can be removed from the shaft 9. When turned down to the position 85 shown in the drawing its face bears against the outer face of the bobbin 4, and since the spring 10 tends at all times to draw it inward it will bear against the bobbin with a yielding pressure, thus causing friction and operating to cause tension on the thread as it is drawn from the bobbin. The end of the arm 12 is bent downwardly over the edge of the bobbin, as shown in Fig. 2, so as to be 90 out of the way within the casing to prevent 100

110

the loop of thread from being accidentally engaged by it.

In revolving hook machines it is necessary in order that the loop of thread may be spread and passed around the bobbin holder that the walls of the holder where the loop is spread shall not be too steep and therefore there is a limit to the angle which can be given to those walls on that side of the holder where the spreading is done. After the loop has been spread, however, and has passed half way around the holder and is being drawn up there is not the same necessity for preventing a steep angle. In other words the thread can be pulled off of the holder on a side where the walls approach the vertical quite closely, as shown in Fig. 2. I have found therefore that by placing the bobbin eccentrically and on the side where the thread will be when being drawn up I am enabled to use a much larger bobbin in a holder of the same circumference, and I have found that it does not affect in any way the smooth and free operation of the take-up. The single arm 12 is used as the retaining means and the tension means, this being rendered possible by the arrangement of the arm at the angle of 45°, as shown, whereby the loop of thread will first strike the outer end of the arm and simply travel up along it and will not be caught by its side or the opposite end.

Having thus described the invention what is claimed as new is:

1. A bobbin holder for rotary hook sewing machines comprising a casing having a circumferential bearing rim formed with a hook and having a circular opening in one side wall to admit a bobbin, the said opening being eccentric to the bearing rim and being more widely separated from that portion of the bearing rim immediately behind said hook than from the diametrically opposite portion of said rim, the side walls extending on an incline from the margin of said opening to the bearing rim, whereby the side walls in that part behind the hook will have a less inclination to the plane of the rim than in the part on the opposite side.

2. A bobbin holder for rotary hook sewing machines comprising a casing having a circumferential bearing rim formed with a hook and having a circular opening in one side wall to admit a bobbin, the said opening being eccentric to the bearing rim and being more widely separated from the bearing rim within that quarter of the circumference immediately behind the hook than in any other portion of the circumference, the side walls of the holder extending on an incline from the margin of the opening to the bearing rim whereby the walls in the quarter behind the hook will have a less in-

clination toward the plane of the rim than the walls in other portions of the holder.

65

3. A bobbin holder for rotary hook sewing machines comprising a casing having a circumferential bearing rim extending throughout the major portion of a circle, and a circular opening in one side wall to admit a bobbin, the said opening being eccentric to said bearing rim, and the side walls being inclined from said rim to the edge of said bobbin holding opening the inclination of the walls being materially greater on one side of the axis of the holder than on the other.

4. A bobbin holder for rotary hook sewing machines comprising a casing having a circumferential bearing rim formed with a hook near the top facing the top and having a circular opening in one side wall to admit a bobbin, the said opening being eccentric to said bearing rim and its axis being in substantially the same horizontal plane as the axis of the rim and on the side opposite to that carrying the hook.

5. A bobbin holder for rotary hook sewing machines comprising a casing having a circumferential bearing rim formed with a hook near the top facing the top and having a circular opening in one side wall to admit a bobbin, the said opening being eccentric to said bearing rim and its axis being in substantially the same horizontal plane as the axis of the rim and on the side opposite to that carrying the hook, a hollow shaft carried by the rear wall of said casing and extending centrally of said opening and adapted to carry the bobbin, a spring retained member in said shaft, a retaining arm pivoted to said member and adapted to lie across said opening extending downwardly at an angle of about forty five degrees on the side carrying the hook.

90

6. In a device of the class described, the combination with a casing having an opening in one side to receive a bobbin, a circumferential bearing rim having a hook at one side near the top facing the top, a bobbin supporting shaft centrally of said opening, a retaining arm carried by said shaft and extending downwardly at an angle of about forty five degrees on the side carrying the hook, and spring pressed means carried by said shaft for pulling said arm inward against the bobbin so as to retard its turning movement and to place the necessary tension on the thread.
